(57) **CLAIM**

The ornamental design for an aerial imaging apparatus, as shown and described.

DESCRIPTION

FIG. 1 is a top front left perspective view of an aerial imaging apparatus showing our new design;

FIG. 2 is a front view thereof, opposite rear view being mirror image thereof;

FIG. 3 is a right side view thereof;

FIG. 4 is a left side view thereof;

FIG. 5 is a top view thereof;

FIG. 6 is a bottom view thereof;

FIG. 7 is another top front left perspective view of the aerial imaging apparatus of FIGS. 1-6, showing the design in an alternative configuration with the optical plate in an opened position;

FIG. 8 is a rear right perspective view of the aerial imaging apparatus of FIGS. 1-6, showing the design in an alternative configuration with the optical plate in an opened position;

FIG. 9 is a front view thereof, with the opposite rear view being a mirror image;

FIG. 10 is a right side view thereof with the optical plate being opened;

FIG. 11 is a left side view thereof with the optical plate being opened; and,

FIG. 12 is a top view thereof with the optical plate being opened.

In FIGS. 1-12, any broken lines shown in the drawings represent portions of the aerial imaging apparatus and form no part of the claimed design.
